ARTHUR A. MCRAE, OF ATTLEBORO, MASSACHUSETTS, ASSIGNOR TO
MCRAE & KEELER, OF ATTLEBORO, MASSACHUSETTS, A FIRM.

HAT-PIN.

SPECIFICATION forming part of Letters Patent No. 793,019, dated June 20, 1905.

Application filed March 28, 1904. Serial No. 200,382.

To all whom it may concern:

Be it known that I, ARTHUR A. MCRAE, a citizen of the United States, residing at Attleboro, in the county of Bristol and State of Massachusetts, have invented a new and useful Improvement in Hat-Pins, of which the following is a specification.

This invention has reference to an improvement in hat-pins, and more particularly to an improvement in the method of securing the head of the hat-pin to the pin-shank.

The object of my invention is to secure the parts forming the head together and to the pin-shank simultaneously without the use of solder.

A further object of my invention is to secure the hat-pin head to the pin-shank more firmly and rigidly than has heretofore been done.

My invention consists in the peculiar and novel construction of a hat-pin having a head formed in halves, with coinciding holes in the top and bottom of the halves, a pin-shank having holes coinciding with the holes in the halves forming the head, and means for securing the halves of the head together and to the pin-shank simultaneously, consisting of rivets through the holes in the head and pin-shank, as will be more fully set forth herein-after.

Figure 1 is a face view of the parts forming my improved hat-pin. Fig. 2 is an edge view of the same, showing the parts in the position to be secured together. Fig. 3 is an edge view of the completed hat-pin. Fig. 4 is a face view of the same, and Fig. 5 is an enlarged vertical sectional view taken lengthwise through the head of the hat-pin and pin-shank.

In the drawings, *a* indicates the pin-shank, *b* the head, and *c c* the tubular rivets for securing the halves of the head together and to the pin-shank.

The pin-shank *a* is formed of spring-wire

and has the usual pointed end *a'*, the flattened end *a''*, in which is the hole *a³*, and the flattened portion *a⁴*, having the hole *a⁵*, as shown in Fig. 1.

The head *b* consists of the halves *b' b'*, having the holes *b² b²* in the bottom and the holes *b³ b³* in the top. The halves *b' b'* are stamped from sheet metal to form a hollow head and may be shaped to form an ornamental design, such as shown in Figs. 1 and 4.

In assembling the parts forming my improved hat-pin the end of the pin-shank having the holes *a³* and *a⁵* is placed between the halves *b' b'* of the head, the hole *a³* in the pin-shank coinciding with the holes *b² b²* and the hole *a⁵* in the pin-shank coinciding with the holes *b³ b³* in the halves *b' b'* forming the head. The tubular rivets *c c* are now passed through the holes in the head and pin-shank and riveted.

By the novel construction and arrangement of the parts of my improved hat-pin the pin-shank extends between the halves forming the head and the head is secured to the pin-shank at the top and bottom of the head by rivets, thus more firmly and rigidly securing the halves of the head together and to the pin-shank simultaneously without solder than has heretofore been done.

It is evident that the pin-shank could be secured to the head without extending it through the head by dispensing with the flattened portion *a⁴* with the hole *a⁵* and securing the flattened end *a''* with the hole *a³* to the bottom of the head by a rivet through the hole *a³* in the shank and the holes *b² b²* in the head. In this modified construction the halves *b' b'* of the head could be secured together at the top by a rivet through the holes *b³ b³* in the top of the head without materially affecting the spirit of my invention.

Having thus described my invention, I claim as new and desire to secure by Letters Patent—

In a hat-pin, the hollow head *b* formed of

the halves $b' b'$ stamped from sheet metal, | each half having the coinciding holes $b^2 b^2$ | and $b^3 b^3$, and means for securing the halves | $b' b'$ together and to a pin-shank, consisting | 5 of the rivets $c c$ through the holes $b^2 b^2$, $b^3 b^3$ | and the pin-shank, as described.

In testimony whereof I have signed my

name to this specification in the presence of | two subscribing witnesses.

ARTHUR A. McRAE.
